UNITED STATES PATENT OFFICE.

HORATIO G. GILLMOR, OF WASHINGTON, DISTRICT OF COLUMBIA.

COMPRESSOR FOR GASES.

1,130,394.

Specification of Letters Patent.

Patented Mar. 2, 1915.

Application filed May 10, 1901. Serial No. 59,567.

To all whom it may concern:

Be it known that I, HORATIO G. GILLMOR, a citizen of the United States, residing at Washington, in the District of Columbia, have invented an Improved Compressor for Gases, of which the following is a specification.

My invention relates to a machine for the compression of gases by the direct application of heat and its objects are to increase the economy and efficiency of the compression of gases by effecting a portion of or the entire compression through heat transmitted to the gases, and to produce a compressor for gases which shall be self-contained and self-driving.

Three embodiments of the invention are set forth in the accompanying drawings, but it will be obvious from an inspection of the claims forming part of this specification that the invention is not limited to the structures shown in the drawings.

Similar letters refer to similar parts in the drawings; in which—

25 Figure 1 is a longitudinal sectional plan of a simple form of the compressor wherein the heat is generated and transmitted directly to the gases within the compression cylinder by the burning of a combustible 30 therein; Fig. 2 is a vertical section of a modified form of the compressor, in which heat is transmitted to the gases through the walls of the compression cylinder, heat being applied externally thereto; and Fig. 3 is a longitudinal sectional plan of a compound compressor in which the compression is effected serially in two stages in cylinders of the type shown in Fig. 1, with the complete mechanism for self-driving.

40 In these figures A is a cylinder casting with one end water-jacketed as at B.

C is a displacer which fits with small clearance within the cylinder A and is capable of linear motion therein; L is the 45 heated end of the compression cylinder; M is the comparatively cool end of the compression cylinder; D is the regenerator of suitable construction; E is a valve which will lift when the pressure in the space M falls below the pressure in the space G and communicating spaces.

F is a check valve which allows the gases to pass from the space M through the passage H to N and communicating spaces, but 55 closes and prevents a back flow of gases

when the pressure in H and M falls below the pressure in N and communicating spaces.

T, Fig. 3 is a working cylinder; U a working piston; R and R¹ are piston rods; V, V¹ and V² are connecting rods; W, W¹ and W² 60 cranks; X a crank shaft; Y a fly-wheel and Z a bed plate or foundation; 4 is a pulley by means of which a motion of rotation may be given to the crank shaft; 5 is a grate or a series of burners for burning fuel of any 65 sort; 6 a flue for the escape of the products of combustion and S lagging to retard radiation or the escape of heat.

I, I¹ are pipes with nozzles or openings P and P¹ through which liquid or gaseous combustible under suitable pressure may be discharged within the cylinder.

O and O¹ are valves for regulating the flow of this combustible and K and K¹ are plugs which may be removed to permit the 75 lighting of combustible at P and then replaced.

In Fig. 1 there is shown a single compression cylinder to which air, or gases capable of supporting combustion, may be supplied 80 at any pressure, whether that of the atmosphere or a higher or lower pressure, through the passage G; communication between the cylinder and the passage being automatically controlled by the valve E. The transfer of gases from one end of the cylinder to the other is effected by means of the crank, connecting rod, piston rod and displacer piston shown. By the pipe I with nozzle P gaseous or liquid fuel, under suitable pressure to overcome the pressure within the cylinder, is discharged at P. The flow of fuel is controlled by the valve O so that the quantity discharged may be sufficient for the purpose, but not in excess of the requirements. The plug K may be removed and the fuel lighted at P. The gases taken into the compressor cylinder are capable of supporting combustion. If then the plug K be replaced, the fuel discharged at P will continue to burn in the gases contained within the cylinder. The heat generated by the combustion will be directly transmitted to the contained gases in the space L, maintaining them at high temperature.

From the foregoing and by reference to the drawings, the action in the cylinder, will be clearly seen and understood to be as follows: It is assumed that the displacer is in such position at the commencement of its 110

cycle of motion that the space L is a maximum and the space M a minimum. The end L of the cylinder is maintained at high temperature by the discharge of fuel through 5 I and P, which burns within the cylinder; and, therefore, the gases in the space L will be at high temperature. Revolution of the shaft X by the mechanism shown causes the displacer C to move and a portion or portions of the hot gases contained in the space 10 L are transferred to the space M through the regenerator D. In this transfer they give up to the surfaces of the regenerator, over which they pass, a portion of their 15 heat; and are further cooled by contact with the surfaces of the cool end of the cylinder. This fall in temperature produces a corresponding fall in the pressure of the contained gases until, by the transfer of a sufficient 20 proportion of the gases from L to M, the pressure within the cylinder becomes slightly less than the pressure in the space G and communicating spaces. The valve E will then lift and further motion of the displacer 25 transferring gases from L to M causes fresh gases to be drawn into the cylinder from G and communicating spaces during the remainder of such motion. The valve E, at the end of the stroke of the displacer, 30 will, by its own weight, fall to its seat.

The further revolution of the driving shaft causes the displacer to move in the direction which enlarges the space L and diminishes the space M, so transferring the 35 comparatively cool gases from the space M through the regenerator D to the space L. During this transfer the gases receive heat from the surfaces of the regenerator over which they pass and in L are further heated 40 by contact with the hot walls of the compression cylinder or by heat generated by the burning of a combustible within the space L. This rise in temperature produces a corresponding rise in pressure which will 45 continue, as more and more of the gases are transferred from M to L, until the pressure within the cylinder is slightly greater than the pressure in the space N and communicating spaces. Further motion of the displacer 50 causing transfer of gases from M to L will cause compressed gases to flow through the check valve F until the end of this stroke of the displacer, when the check valve will close and prevent any back flow of gases during 55 the following stroke of the displacer.

It will thus be seen that, if the two ends of the cylinder be maintained at a suitable difference of temperature and proper arrangement be made to add heat to the gases when 60 in the space L, motion of the displacer by transferring the gases alternately through the regenerator from L to M and from M to L, during one complete cycle of motion, will then cause gases, during one portion of the 65 stroke, to be drawn into the cylinder at the

pressure existing in the space G and communicating spaces; and, during another portion of the stroke, to be discharged at a higher pressure through the passage H and the check valve F into the space N and communicating spaces. Each repetition of this 70 cycle will produce similar results; and the ratio between the pressure of the gases taken in and their pressure when discharged from any such cylinder, and the quantity so discharged during cycle of motion, will depend primarily upon the difference in temperature 75 of the gases when in the spaces L and M.

In Fig. 2 is illustrated a modified form of the invention which differs from that shown in Fig. 1, in that heat is transmitted to the gases in the space L through the walls of the compression cylinder, heat being applied externally thereto, and that gases of any kind, whether capable of supporting combustion or not, may be supplied at any pressure through the passage G. The walls of the end L of the compression cylinder are externally heated by fuel burned on a grate 5, or in a series of burners properly disposed below the surface, the products of combustion escaping by the flue 6. The lagging S prevents or retards the dissipation of heat by radiation from the surfaces to which it is applied. The walls of the end L of the compression cylinder are maintained in this manner at as high a temperature as is consistent with the physical characteristics of the material of the walls or as the circumstances may permit or require; and heat 90 transmitted through them to the gases contained in the space L. The motion of the displacer piston effecting the transfer of gases from one end of the cylinder to the other is produced by the crank connecting 95 rod and piston rod shown.

It will readily be seen and understood that the principle of operation of the form of compressor shown in Fig. 2 is the same as that of the form of compressor shown in Fig. 1; and that the motion of the displacer piston will, as described above, effect the periodic introduction of fresh gases from the passage G into the cylinder; and the compression and discharge during each cycle, through the valve F and the passage N of an approximately equal amount of gases at higher pressure.

It will readily be seen and understood that by combining two or more such compression cylinders of either of the forms shown in Figs. 1 and 2 with their displacers, regenerators, etc., and so arranging them that the gases discharged from one cylinder will pass into the succeeding cylinder (or into a reservoir or receiver from which the succeeding cylinder may take gases) the compression may be effected by steps or stages to obtain a desired pressure of the gases at final discharge from the com- 120 125 130

pressor. The action in each cylinder will be as described above, a certain change in pressure being effected in each.

In Fig. 3 there is shown such a compound compressor, in which the compression is effected serially in two steps or stages in cylinders of the type shown in Fig. 1, fitted with self-driving mechanism. In this compressor the cranks W and W^1 are approximately opposite or about 180 degrees apart so that the displacers are moving in opposite directions. While then the displacer C is moving in the direction indicated by the arrow and transferring gases from the space M to the space L so producing a rise in pressure, as described above; the displacer C^1 in the adjacent cylinder is moving in the opposite direction and transferring gases from the space L^1 to the space M^1 , so producing a fall in pressure in that cylinder. When then the pressure in M becomes enough in excess of that in M^1 to cause the valve E^1 to lift a flow of gases from M to M^1 will commence and will continue to the end of that stroke of the displacer. Upon the return stroke, the valve E^1 is closed by its own weight and the pressure of the gases above it and the fall in pressure in the first cylinder, produced by the transfer of gases from L to M , will cause fresh air to enter through the ports G . At the same time the transfer of gases from M^1 to L^1 will produce a rise in pressure within that cylinder and the discharge through the check valve F of a certain portion or portions of the gases, in the manner described above for the single cylinder.

A compound compressor in which the compression is effected serially in a greater number of cylinders may be constructed in a similar manner. In the machine shown in Fig. 3, the heat is added to the gases by the burning of the combustible within the space L . A combination of externally heated compression cylinders, such as that shown in Fig. 2 might be effected similarly with the same purpose and results.

The motion of the shaft and mechanism for producing the movements desired in the displacer or displacers above described, may be effected by driving the said shaft by means of a pulley and belt, by gearing or by any other suitable device or devices such as motors driven by electricity, compressed gases, steam, vapors, etc. To make the compressor self-contained and self-driving, however, I prefer to arrange the driving mechanism as shown in Fig. 3, where T is a working cylinder in free communication with the space M of the compression cylinder; U a working piston of the type commonly employed in gas engines; V^2 a connecting rod; W^2 a crank on the shaft X ; and Y a fly-wheel. The crank W^2 is at an angle of about 90 degrees to the crank W ,

driving the displacer of the compression cylinder with which it communicates; so that, when the piston U is about to commence its outward stroke, the displacer C is somewhere near midstroke and moving outward. 70 The pressure of the gases in M will, therefore, be either rising or be the pressure at which gases escape or are discharged from the first cylinder. The piston U will therefore move outward doing work in overcom- 75 ing the frictional and other resistances in driving the mechanism and in accelerating the fly-wheel and moving parts. After the displacer C reaches the limit of its stroke and begins the return stroke, the pressure 80 will fall and when the pressure within the compression cylinder has fallen sufficiently the valve E will lift and admit fresh gases through the ports G . The working piston will begin its return stroke when the displacer is at somewhere about midstroke and moving toward L and a portion of the return stroke of the working piston will be effected against a pressure about that of the atmosphere, until by the motion of this piston and the displacer the pressure within the cylinder begins to rise; after which the remainder of the stroke of the working piston would be effected against a rising pressure. 85 Work would therefore be being done 90 during the return stroke of the working piston in overcoming frictional and other resistances and the pressure of the gases in the space M . The energy necessary for this work will be given out by the fly-wheel having been given thereto during the out or working stroke of the piston U , the function 95 of the fly-wheel in this case being well known and understood and directly similar to its action in the gas engine and other 100 mechanisms in which there are fluctuations in the supply of energy. The effect then of the combination of the working cylinder, communicating freely with the space M and having its motion related to the motion of 105 the displacer in the manner indicated, is to produce such continuous rotation of the crank shaft X as is necessary to the operation of the compressor, so long as sufficient 110 difference in temperature is maintained between the spaces M and L .

The driving mechanism described above may be applied to a single cylinder or simple compressor in the manner described and shown for the first cylinder of the two stage 115 or compound compressor, its action being as described above.

In applying the driving mechanism to a compound or multiple stage compressor it might be applied to any compression cylinder in the series as well as to that shown in Fig. 3.

While in the above description of the driving mechanism, I have mentioned 90 degrees as the approximate angle between the 130

crank for the working cylinder and that of the compression cylinder, I do not limit myself to that angle or angles closely approximating to it; since by experiment it might be found that other angles might serve equally well or better for the purpose. It will be understood also that eccentrics, cams, or other mechanical devices may be employed in place of cranks.

10 I have shown the regenerators indicated as D and D⁴ in the several plans as being formed in a passage or passages in the displacer itself. They might also be constructed or formed in independent passages communicating with the spaces L and M and not move with the displacer; and the displacer would, in this case, be without passages and as light as consistent with the conditions.

Obviously, the invention may be embodied 20 in widely varying forms within the scope of the artisan; therefore, without limiting the invention to the constructions shown or described, or enumerating equivalents, I claim, and desire to secure by Letters Patent, the 25 following:

1. A compressor for gases including, in combination with a compression cylinder provided with means whereby one end thereof may be maintained at relatively high 30 temperature, and means whereby the walls of the other end thereof may be cooled, a displacer piston adapted to move within said compression cylinder, a regenerator through which gases may be transferred 35 from one end to the other of said compression cylinder by movements of said displacer piston, a valve for the admission of gases to and a valve for the discharge of gases from said cylinder.

40 2. A compressor for gases including, in combination with a plurality of compression cylinders of suitable sizes provided with means whereby one of the ends of each may be maintained at relatively high temperature and means whereby walls of the other ends thereof may be cooled, displacer pistons adapted to move within said compression cylinders, means whereby suitable motions may be produced and maintained in 45 said displacer pistons, valves for the admission of gases to and valves for the discharge of gases from said compression cylinders.

3. A compressor for gases, comprising a 55 plurality of compression cylinders of suitable sizes provided with means whereby one of the ends thereof may be maintained at relatively high temperature, and means whereby the walls of the other ends thereof may be cooled, displacer pistons adapted 60 to move within said compression cylinders, valves for the admission of gases to, valves for the discharge of gases from said cylinders, a working cylinder communicating at one end with one of said compression cylinders, a working piston adapted to move

therein, and means whereby suitably related motions are transmitted to the said working piston and said displacer pistons.

4. In a compressor for gases the combination with compression cylinders, one of the 70 ends of each of which may be maintained at high temperature while the other ends thereof are maintained at comparatively low temperature, of displacer pistons located therein, regenerators in free communication with 75 the two ends of the said compression cylinders, valves for the admission of gases to and valves for the discharge of gases from the said compression cylinders, and means whereby suitable motions are transmitted to 80 and maintained in said displacer pistons.

5. In a compressor for gases the combination with compression cylinders, one of the 85 ends of each of which may be maintained at high temperature while the other ends thereof are maintained at comparatively low temperature, of displacer pistons located therein, regenerators giving free communication 90 between the two ends of each of the said compression cylinders, valves for the admission of gases to and valves for the discharge of gases from the said compression cylinders, a working cylinder on and 95 communicating with one of said compression cylinders, a working piston within the said working cylinder, and a mechanism to impart to and maintain in said displacers and working piston suitable motions.

6. A gas compressor including, in combination with a plurality of compression cylinders constructed with combustion chambers communicating with the interiors of one of the ends thereof and means whereby the walls of the other ends thereof may be cooled, displacer pistons adapted to move 100 within said cylinders, valves constructed to admit gases to said cylinders, valves constructed to permit the discharge of gases from said cylinders, and means whereby a combustible fuel may be discharged and 105 burned in said combustion chambers.

7. In a compressor for gases, the combination of compression cylinders each having a combustion chamber communicating therewith, displacer pistons adapted to move 110 therein, regenerators communicating freely with the two ends of said cylinders, inlet valves adapted to admit gases to the several cylinders, a valve adapted to permit the discharge of gases from the said cylinders, and 115 means for the introduction of combustible into the said combustion chambers.

8. In a compressor for gases the combination with a compression cylinder, a displacer piston therein, a regenerator and valved 120 inlets and outlets, of another compression cylinder of suitable size, a displacer therein, a regenerator and valved inlets and outlets, and means whereby said displacer pistons 125 may be made to reciprocate.

9. In a compressor for gases the combination with a compression cylinder, a displacer piston therein, a regenerator and valved inlets and outlets, of another compression cylinder of suitable size, a displacer piston therein, a regenerator and valved inlets and outlets, a working cylinder on and communicating with one of the said compression cylinders, a working piston in the said working cylinder, and means whereby said displacer pistons may be made to reciprocate.

10. A gas compressor including, in combination with a compression cylinder, piston, admission and discharge valves, a second compression cylinder provided with means whereby one end thereof is maintained at higher temperature than the other end thereof, a displacer piston adapted to move in said cylinder, valves controlling the admission of gases to, and the discharge of gases from, said cylinder, and means whereby said displacer is made to reciprocate.

11. A gas compressor comprising a plurality of compression cylinders, each provided with heating means for maintaining one end thereof at higher temperature than the other end, displacers adapted to move in said compression cylinders, valves for controlling the admission of gases to, and the discharge of gases from, said compression cylinders, a working cylinder communicating at one end with one of said compression cylinders, a working piston adapted to move in said working cylinder, actuated by compressed gases, and means whereby the motion of said working piston is transmitted to said displacers.

12. The combination of a plurality of compression cylinders, each provided with heating means to maintain one end thereof at higher temperature than the other end thereof, displacer pistons adapted to move therein, and valves arranged to control the admission of gases to, and the discharge of the same from, said cylinders, with a working cylinder communicating with one of said compression cylinders, a working piston actuated by the compressed gases, and means for transmitting the movements of said working piston to said displacers.

13. The combination of a gas compressor and a compression cylinder provided with means whereby one end thereof may be maintained at relatively high temperature and arranged to receive gases discharged by said compressor, a displacer piston adapted to move within said compression cylinder, valves controlling the admission of gases to, and the discharge of gases from, said cylinder, and means whereby a reciprocating motion may be transmitted to said displacer piston.

14. A gas compressor, including, in combination, two compression cylinders connected by a valve controlled passage whereby gases may be discharged from one of said cylinders to the other, a displacer piston adapted to move within one of said cylinders, a regenerator through which gases contained in said cylinder may be transferred from one end to the other of said cylinder by movements of said displacer piston, means whereby reciprocating motion may be transmitted to and maintained in said displacer piston, and a valve-controlled passage whereby gases may be admitted to and discharged under pressure from said compressor.

15. A gas compressor including, in combination, a compression cylinder arranged with heating means whereby one end thereof is maintained at higher temperature than the other end thereof, a displacer piston adapted to move therein, and means for producing reciprocating motion in said displacer.

16. The combination of a gas compressor and a compression cylinder having a combustion chamber and means for supplying and burning fuel to maintain one end thereof at relatively high temperature, a displacer piston adapted to move within said compression cylinder, means whereby said displacer piston may be made to reciprocate, and valves for controlling the admission and discharge of gases.

17. The combination of a gas compressor and a compression cylinder provided with heating means for one end thereof, a displacer adapted to move in said cylinder, a regenerator arranged to alternately withdraw and add heat to gases passed through said regenerator by movement of said displacer, means for reciprocating said displacer, and valves controlling the admission and discharge of gases.

18. The combination of a gas compressor and a compression cylinder having a combustion chamber and fuel supplying and burning means for heating one end thereof, a displacer adapted to move within said cylinder, means for reciprocating said displacer, a working cylinder communicating with said compression cylinder, a working piston actuated by the gases, and means whereby the motion of said working piston is transmitted to said displacer.

In testimony whereof I have signed my name to this specification in the presence of two subscribing witnesses.

H. G. GILLMOR.
